UNITED STATES PATENT OFFICE.

JOSEPH YARDLEY JOHNSTON, OF LONDON, ENGLAND, ASSIGNOR TO THE JOHNSTON NORTH AMERICAN PATENTS COMPANY, LIMITED, OF SAME PLACE.

DIE CLAMP AND GUARD.

SPECIFICATION forming part of Letters Patent No. 677,225, dated June 25, 1901.

Application filed January 23, 1900. Renewed April 23, 1901. Serial No. 57,118. (No model.)

To all whom it may concern:

Be it known that I, JOSEPH YARDLEY JOHNSTON, a citizen of the United States of America, residing at the city of London, England, have 5 invented a Die Clamp and Guard, of which the following is a specification.

This invention has reference to means for clamping or holding in position the dies or the like of printing or printing and embossing 10 presses and for regulating contact between said dies or the like and the inking devices of the press.

Referring to the accompanying drawings, Figure 1 is a sectional view on the line A A, 15 Fig. 4, of the clamping and regulating means, the die and the block to which it is secured being indicated in dotted lines. Fig. 2 is a side view thereof. Fig. 3 is a similar view to Fig. 1, partly in section. Fig. 4 is a plan 20 thereof. Fig. 5 is an end view, Fig. 4, certain parts being omitted. Fig. 6 is a detail sectional plan, and Fig. 7 represents to a smaller scale a die secured to its block and provided with regulating means in the act of being 25 inked.

The die *a* is shown secured to a rectangular block *b*, furnished with a square shank adapted to slide vertically in a square opening at the end of a die-arm which is revolved 30 over inking and wiping apparatus prior to printing, and the said block may be held normally in contact with the under side of the arm by suitable springs, as indicated in Fig. 7. A dovetailed groove *c*, formed horizontally across the under side of the block *b*, receives dovetailed projections *e* and *f*, formed, respectively, on clamp-jaws *g* and *h*, operated by a right and left handed screw *i*, held longitudinally by plates *j*, secured to the die-block *b*. An index-plate *k*, formed with a series of recesses *l*, corresponding to the graduations of the index, is arranged to slide in a groove *m*, formed in the die-block at right angles to the dovetailed groove *c* and to be 40 secured in the desired position by a screw-pin *n*, which enters any one of the recesses *l*. The clamp-jaws *g* and *h* automatically center the die in one direction, and by pushing it against the end of the index-plate *k* previous 45 to clamping its correct position in the oppo-

site direction may be insured. Thus a die can be removed by simply loosening the screw *i* and replaced exactly in its previous position, thus insuring correct register. In place of the above-described index-plate two plates 55 or stops operated by a right and left handed screw at right angles to the aforesaid screw *i* may be employed to automatically center or locate the die longitudinally, and in place of the dovetailed arrangement above described 60 the clamp-jaws *g* and *h* may be provided with projections at the ends to embrace and slide upon the edges of the block *b*, said edges and projections being of dovetail form, if desired, or any other suitable means may be employed 65 for this purpose.

Upon the clamp-jaw *g*, which is at the leading or forward edge of the die *a*, I provide adjustable-guards *o*, adapted to operate upon the inking-roller of a spring-supported inking 70 apparatus at the required time, so as to depress the said inking-roller and only allow it to rise when the front edge of the die *a* has passed, whereby the said front or leading edge of the die is prevented from becoming 75 charged with ink and from catching against and damaging the inking-roller. The guards *o* are carried by the ends of the clamp-jaw *g*, which extend beyond the dye-block *b*, each of said ends being formed with a rectangular 80 opening *p*, in which one of the guards *o* is free to slide vertically, but is confined therein by a plate *q*, secured to the end of the jaw. The guards are adjusted and supported by screws *r*, that extend into plain grooves *s*, Figs. 85 3 and 6, in the wall of the openings *p*, end-wise motion of each screw being prevented by a semicircular collar *t* at the end of the groove entering an annular recess *u* beneath the screw-head. The thread of each screw *r* 90 engages a half-nut *v*, formed in the side of the guard *o*, each of which is provided with a renewable wearing-piece *w*, with inclined forward edge, as shown. The guards are so adjusted that their horizontal under surfaces 95 are slightly above the face of the die, but that when the guards are in contact with disks *x*, Fig. 7, carried by the inking-roller spindle, said roller is held below the die-face. As soon as the guards clear the disks *x* 100

springs γ force the inking-roller up again, so that it comes in contact with the die just beyond its leading edge, and therefore no ink is delivered on the front edge of the die. The 5 die now travels over the inking-roller, which is pressed against it by the said springs and becomes charged with ink.

The distance from the edge of the die to the 10 place where the inking-roller meets its face is regulated solely by the vertical adjustment of the guards σ , which may be effected independently, so as to suit varying positions of the inking-roller.

The rear clamp-jaw h is inclined, as shown, 15 Fig. 2, to prevent it making contact with the inking-roller after the die has passed the same.

What I claim is—

1. In a printing-press, the combination of 20 an inking device, die-clamping jaws of which the forward or leading jaw is formed with lateral extensions and adjustable means carried by said extensions for regulating contact between said die and the inking device 25 of the press, as set forth.

2. The combination with a die-clamping jaw having lateral extensions each formed with an opening, of a vertically-adjustable block located in each of said openings and 30 means for adjusting said block, as set forth.

3. The combination with a die-clamping

jaw having lateral extensions each formed with an opening, of a vertically-adjustable block located in each of said openings and 35 formed with a renewable wearing-surface and means for adjusting said block, as set forth.

4. The combination with a die-clamping jaw having lateral extensions each formed with an opening, of a vertically-adjustable block located in each of said openings and 40 formed with a renewable wearing-surface and with a half-nut, a screw engaging in said half-nut and means for preventing said screw moving longitudinally, as set forth.

5. The combination with a die-block having 45 a dovetail groove of a pair of clamp-jaws each formed with projections fitting in said groove, means for causing said clamp-jaws to move toward and from each other, vertically-adjustable blocks contained in openings 50 formed in lateral extensions of the forward or leading clamping-jaw, and having renewable wearing-surfaces and half-nuts, screws engaging in said half-nuts and each formed with a recess into which a part collar formed 55 on the clamp-jaw enters, as set forth.

Signed at 22 Bride Lane, London, England, this 12th day of January, 1900.

JOSEPH YARDLEY JOHNSTON.
